2,086,666

PROCESS FOR DEWAXING OIL

Harmon F. Fisher, Los Angeles, Calif., assignor
to Union Oil Company of California, Los
Angeles, Calif., a corporation of California

Application August 21, 1933, Serial No. 686,015

6 Claims. (Cl. 204—24)

This invention relates to wax separation from wax-bearing oil. The invention relates more particularly to the separation of precipitated wax from suspensions in oil.

5 Many crude oils from which lubricating oil is produced contain paraffin or wax. It is found associated with lubricating oil fractions of paraffin base crude oil, asphalt base crude oil and the mixtures or blends of lubricating oil fractions of 10 both paraffin and asphalt base crude oils. The wax is not only of limited lubricating value but limits the minimum temperature at which lubricating oils containing it can be used, by congealing at low temperatures. Therefore, in the 15 production of lubricating oil from petroleum fractions containing wax and paraffin, it is customary to remove a substantial portion of the wax and paraffin present in the oils in order to lower its pour point and the temperature at which it congeals.

The separation of wax from wax-bearing lubricating oil fractions has been accomplished by several processes in the past. The most common and oldest of which are the "cold settling process" 25 and the "cold pressing process".

In the "cold settling process" the wax-bearing oil is first diluted with a quantity of a light hydrocarbon fraction, such as naphtha, gasoline or kerosene. The diluted wax-bearing oil is then 30 slowly chilled by suitable refrigerating means for a period of from twenty to fifty hours until a temperature is reached at which a substantial portion of the wax is precipitated. The chilled oil and precipitate mixture is then allowed to 35 stand for a period of several weeks to allow the wax to settle to the bottom of the chilling tank. Objections to this process are the cost of refrigeration for the necessary long periods of time, the large capacity of refrigeration and storage 40 equipment necessary and the poor separation of wax and oil obtained.

In the "cold pressing process" the wax-bearing oil is chilled slowly, as in the above described "cold settling process". The chilled mixture of 45 precipitated wax and oil is then pumped through a filter press at a high pressure. The wax is collected upon the filter and the oil is removed as a pressed distillate relatively free from wax. This process has found commercial application only 50 in conjunction with oil having wax present in a crystalline form. The other forms of wax, such as amorphous and micro-crystalline wax have been found extremely difficult and impracticable to separate by filtration methods.

55 It has been found that the enumerated disadvantages and other disadvantages inherent in the common methods of wax separation methods may be overcome by the process which will be described hereafter.

60 It has been discovered that wax can be readily

separated from wax-bearing oils by mixing the wax-bearing oils with suitable diluents, chilling the solution to a temperature at which the wax precipitates from solution and the resulting mixture of wax-bearing oil, diluent and precipitated wax, subjected to an electric field. A major portion of the precipitated wax acted upon by the electric field is separated from the mixture in the form of a deposit on the electrodes between which the said treating field is established. That portion of the precipitated wax which is not removed from the mixture in the form of a deposit is agglomerated or otherwise conditioned to more readily separate from the mixture by settling. The diluent may be recovered by distillation subsequent to the separation of the wax from the solution and recycled through the system, according to the process described above.

Diluents are usually employed during dewaxing by these methods to render the waxy oil fluid at 20 the temperatures at which the wax is precipitated out of solution. However, the presence of a large quantity of diluent in the wax-bearing oil is always detrimental by reason of its solvent action upon the wax. Even at the lower temperatures 25 many diluents retain an appreciable amount of wax in solution. Therefore, when large quantities of diluent are employed during dewaxing a relatively higher pour point is obtained in the final product due to the wax retained in solution 30 in the diluent. Furthermore, it is undesirable to use large quantities of diluent because of the added cost in recovering these materials from the dewaxed oil product.

Therefore, it is desirable to employ a minimum 35 quantity of diluent in the wax-bearing oil while subjecting it to treatment for the removal of wax according to the methods described hereinbefore. Moreover, it is desirable when the characteristics of the lubricating oil permit, to treat the oil according to the hereinbefore described methods 40 without the use of diluents.

The preferred method according to this invention comprises treating the undiluted wax-bearing oil in a number of stages of successively lower 45 temperatures as follows: The wax-bearing oil is chilled in the first stage of treatment to a temperature at which wax is precipitated from solution. Following this the mixture of wax-bearing oil and wax precipitate thus formed is treated by 50 an electric field to deposit and otherwise remove the precipitated wax from the oil. Then the oil from which the precipitated wax has thus been removed in the first stage of treatment is further cooled in a second stage of treatment to 55 precipitate additional wax from the oil. The wax-bearing oil, wax precipitate mixture thus formed in the second stage of treatment is again subjected to an electric field, as in the first stage, to remove additional precipitated wax. These 60

steps are repeated through any desired number of stages of treatment, the precipitated wax being removed electrically in each stage, in the manner described for the first and second stages, until the 5 temperature at which wax will precipitate from solution is reduced to the desired pour point temperature of the oil.

It has been found that wax-bearing oil can be dewaxed by this method in many cases without 10 the use of diluents. Some undiluted wax-bearing oils are solid at ordinary temperatures and when this condition obtains the said wax-bearing oil is heated in the initial stage or stages of treatment to a temperature at which the wax-bearing oil is 15 sufficiently fluid yet contains precipitated wax. Thus each stage of treatment is carried on at a suitable temperature between the cloud point temperature and the congealing temperature of the wax-bearing oil where the fluidity of the resulting mixture of wax-bearing oil and wax precipitate is suitable for efficient electrical treatment and deposition of the precipitated wax. When it is desired to operate the various stages of treatment at a lower range of temperatures 20 than is possible with undiluted oil, the wax-bearing oil is dissolved in a suitable quantity of diluent before being subjected to the said stages of treatment.

The addition of certain electrolytes to the wax-bearing oil or the wax-bearing oil-diluent solution prior to or during refrigeration and electrical treatment has been found to aid in the separation of precipitated wax from the oil by 30 electrical treatment. The electrolyte in solution 35 is also beneficial in obtaining thorough and efficient separation of the undeposited precipitated wax from the solution by settling. Electrolytes which have been found suitable in aiding separation are: inorganic acids, such as sulphuric, 40 hydrogen chloride; organic acids, such as formic, acetic, oleic, stearic, naphthenic and palmetic; metallic halides, such as aluminium chloride, ferric chloride, stannic chloride and zinc chloride. Also solutions of sulphur dioxide, carbon dioxide, 45 ammonia and numerous soluble organic bases act as electrolytes to aid in the separation of the precipitated wax. The electrolyte may be introduced into the wax-bearing oil or into the diluent prior to their mixture, refrigeration and 50 electrical treatment.

The addition of finely divided substances to the wax-bearing oil prior to refrigeration aids in settling, agglomeration and deposition of the precipitated wax and these substances may be 55 mixed with the wax-bearing oil or the diluent prior to their introduction to the stages of treatment.

In some cases it is advantageous to introduce 60 simultaneously finely divided solids and electrolytes into the wax-bearing oil, or into the wax-bearing oil-diluent solutions which are undergoing treatment. Finely divided materials which I have discovered to be applicable to this process are iron, aluminium, lead, zinc, tin, litharge, 65 graphite, iron oxide, carbons, such as lamp-black or gas-black, asphalt, diatomaceous earth, clay, sawdust or wood flour.

The wax-bearing oil may be dissolved in a diluent prior to refrigeration according to the process 70 described above for the purpose of preventing the refrigerated wax-bearing oil from congealing and to maintain the mixture sufficiently fluid to allow the precipitated wax to be readily separated from the mixture. Diluents which I have found suitable for this purpose are propane, 75

pentane, butane, petroleum ether, naphtha, gasoline, kerosene, acetone, benzol, mixtures of acetone and benzol, methylchloride and halogenated hydrocarbons, such as monochlorodifluoromethane, dichlorodifluoromethane and dichloroethylene and trichloroethylene, ethers, alcohols and various mixtures thereof. A number of these solvents, such as propane, butane and methylchloride are normally gaseous and may, by a reduction of pressure, be made to serve 10 as refrigerants as will be described hereinafter.

Refrigeration of the wax-bearing oil-diluent solution is accomplished either by means of external indirect heat exchange with a refrigerant, internal indirect heat exchange by means of a 15 refrigerant circulated through cooling coils or by direct cooling by means of evaporation of a normally gaseous liquid diluent from the wax-bearing oil solution. It has also been found possible to cool the contents of the electrical treaters 20 chambers by evaporation therein of liquid sulphur dioxide, carbon dioxide or ammonia.

The currents and/or potentials preferably employed in treating the refrigerated wax-bearing oil or solution of wax-bearing oil and diluent, 25 containing precipitated wax, are either continuous direct current or interrupted direct current. When direct current either continuous or interrupted is employed, deposition of a portion of the precipitated wax on the electrodes immersed 30 in the mixture takes place and the remainder of the precipitated wax is agglomerated, or otherwise effected, so that it is readily settled from the solution. An alternating potential may also be imposed upon the solution containing precipitated wax to agglomerate the wax and render it more readily separated by settling. Potential gradients of 5,000 to 60,000 volts per inch through the solution containing precipitated wax have been found most effective for deposition and 40 agglomeration. Some precipitates exhibit a definite negative charge and are, therefore, deposited in greatest quantity on the positive electrode.

Materials which have been effectively used for 45 electrodes are iron, aluminium, copper, zinc and lead.

Objects of this invention are to overcome the 50 enumerated disadvantages and other disadvantages of the common wax separation methods and to provide a novel process for separating wax from oil which will be efficient, economical, of high capacity and less costly in time and equipment than the processes heretofore employed. Other objects are to provide a process for the 55 separation of precipitated wax from wax-bearing oil which will be complete, in which the time of separation of the wax is greatly reduced and in which the time and energy consumption of refrigeration is a minimum and by which fine precipitates both crystalline and amorphous can be effectively separated. Another object of this invention is to provide a process for the separation of wax from wax-bearing oil in stages of successively lowered temperatures. Another object of 60 the invention is to provide a process for dewaxing oil in which the quantity of diluent employed in connection therewith can be minimized or entirely eliminated. Another object of this invention is to provide a method for separating wax 65 which has been precipitated by quickly cooling or "shock chilling" the wax-bearing oil.

In general these objects are attained according to this invention through treating the mixture of oil and precipitated wax by an electrical 75

field or current. These objects are also attained according to this invention through electrically treating the wax-bearing oil and/or wax-bearing oil-precipitate mixture in a plurality of stages 5 at successively lower temperatures with a separation of a portion of the wax from the oil in each stage. These objects are also attained according to the invention through the combined treatment by chemicals and/or finely divided solid materials and electrical treatment in stages 10 at successively lower temperatures.

The invention, broadly stated, comprises a method of separating wax from wax-bearing oil electrically in a plurality of stages, these stages 15 being at successively lower temperatures. The invention more specifically stated comprises a multi-stage process for treating either undiluted wax-bearing oil or wax-bearing oil dissolved in a diluent, by an electric field or current to separate wax therefrom by agglomeration, settling and/or deposition, each stage comprising cooling the wax-bearing oil to precipitate wax, subjecting the thus formed wax-bearing oil-wax precipitate mixture to an electric field and removing 20 the precipitated wax from the oil. The invention also comprises the combined method of treating wax-bearing oil with chemicals and/or finely divided solid materials and an electric field or current in a plurality of stages at successively 25 lower temperatures to aid in separation of the wax therefrom. The invention specifically stated consists of a process for removing wax from wax-bearing oil comprising adjusting the temperature of the wax-bearing oil to precipitate wax 30 from solution, subjecting the mixture of wax-bearing oil and precipitated wax to an electric field, separating the precipitated wax from the oil, reducing the temperature of the wax-bearing oil from which the wax has been separated to precipitate additional wax, subjecting the mixture 35 of the said wax-bearing oil and additionally precipitated wax to an electric field, separating additionally precipitated wax from the oil and so on, repeating the above described steps through any 40 required number of stages, each at reduced temperature for the removal of sufficient wax to obtain the desired pour point oil.

Other objects, advantages and features of the invention will be evident hereafter.

50 The preferred structure of each electrical treater unit comprises a gas tight, vertical cylinder having an upper spherical head and an inverted conical bottom with a cylindrical electrode situated axially within the electrical treater shell and supported by and electrically connected through a high tension lead-in insulator extending through the center of the said top spherical head. The electric treating potential is maintained between said cylindrical electrode and the 55 wall of the treater shell by means of a high voltage generator or transformer through suitable electrical connections. The precipitated wax which settles out of the wax-bearing oil and the wax which is removed from the treater walls and electrode surfaces moves downward toward the 60 apex of the inverted conical bottom of the electrical treater shell where it enters a pump by means of which it is ejected from the system. Refrigeration of the contents of the electrical treater units may in some cases be directly attained by evaporation of a normally gaseous liquid from solution with the waxy oil undergoing treatment in the treater. The treater shell is, therefore, constructed to withstand the pressures associated with 65 this type of operation. Cooling coils may also be

provided in the inside of the electrical treater shell through which a refrigerant may be circulated for the purpose of cooling the treater contents or maintaining its temperature constant. The wax-bearing oil or wax-bearing oil- 5 diluent solution is introduced at a point in the electrical treater shell about midway between the top and bottom. The electrical treater outlet is situated near the top thereof. In the case where a normally gaseous diluent is employed 10 as a refrigerant, a gas space is maintained in the top of the unit and suitable gas outlet and pressure regulator connections provided. Mechanical means, such as scrapers or stirrers may be provided for continuously or intermittently removing 15 deposited wax from the walls and electrodes of the electrical treater and directing it to the outlet in the conical bottom. A periodic reversal of the polarity of the electric potential impressed upon the electrodes in the treaters has been 20 found effective in many cases in removing deposited wax. Upon reversal of polarity the deposited wax is observed to be suddenly broken away in large pieces and momentarily repelled from the electrode, after which redeposition and continued deposition of the wax immediately takes 25 place. The deposited wax particles thus removed from the electrode surfaces, if allowed a short settling period without imposition of electrical potential thereupon, rapidly settle through 30 the oil to the bottom of the treating chamber from which they are readily removed. In some cases where mechanical or other means for removing wax from the treater walls and electrodes are not used it has been found satisfactory to 35 utilize a battery of two or more treaters in parallel so that they can be operated intermittently or alternately allowing the ones not in operation to be entered and the accumulated wax removed.

The accompanying drawing illustrates one 40 embodiment of the invention in which:

Figure 1 is a diagram of apparatus by means of which the process of multi-stage dewaxing can be carried on.

Figure 2 is a graph showing the physical states 45 for a given wax-bearing lubricating oil under varying conditions of temperature and wax percentage.

Wax-bearing oil at a temperature above its congealing point is stored in tank 10. This wax-bearing oil is withdrawn from tank 10 by pump 11 and forced through line 12, valve 13, mixing valve 14, line 15, refrigerator 16 and valve 17 into the first stage treater unit A. The wax-bearing oil is chilled in refrigerator 16 to a temperature sufficiently low to cause precipitation of a portion of the wax from the oil yet to a temperature insufficiently low to cause the mixture to congeal or to cause the mixture's fluidity to be materially reduced. The chilled oil containing 50 precipitated wax, in treater unit A, is subjected to an electric field between the treater wall and the electrode 20, resulting in a major portion of the wax precipitate being removed from the oil and deposited on the electrical treating chamber 55 wall and electrode. This deposited wax, along with other wax which settles, is removed from the interior surfaces of the electrical treater chamber A and withdrawn from the conical bottom thereof by means of pump 21. A high potential electric field is established through the oil containing precipitated wax in the electric treater A between the central electrode 20 and the treater wall by means of a high voltage supplied by a generator 25 through requisite electrical connec- 60 65 70 75 80 85 90 95 98

tions comprising conductor 26, switch 27 and treater lead-in insulator bushing 28. The electrical return circuit from the treater shell is completed through the ground and the generator ground connection 30. The electrically treated wax-bearing oil from which wax has been removed in the first stage electric treater A is withdrawn therefrom through line 35 and passes through refrigerator 36 and valve 37 into the second stage electric treater unit B. The said wax-bearing oil from treater A is again reduced in temperature while passing through refrigerator 36 to a point where additional wax is precipitated from solution but to a temperature insufficient, as in the first stage of cooling, to materially reduce the fluidity of the mixture. Here, as in the first stage of treatment, the wax-bearing oil containing precipitated wax is subjected to an electric field between the treater wall and the electrode 40 where precipitated wax is removed from the said wax-bearing oil by deposition and settling. The deposited wax removed from the treater wall and electrode 40 of unit B along with that which settles, is removed from the conical bottom by means of pump 41. The high potential electric field established through the solution containing precipitated wax in the treater unit B between the wall of the electrode 40 is supplied by the generator 25 through electrical connection 26, switch 42 and lead-in insulator bushing 43. The electrical return circuit from the treater shell is completed through the ground and ground connection 30. The wax-bearing oil from which a portion of the wax has been removed in the first and second stages of treatment in treater units A and B is withdrawn from the second stage treater B through line 45 and introduced through refrigerator 46 and valve 47 into the third stage electric treater unit C. The wax-bearing oil, as in the first and second stages, is again reduced in temperature by refrigerator 46 to a point where additional wax is precipitated from solution yet to a temperature insufficient to materially decrease the fluidity of the resulting mixture of wax-bearing oil and precipitate. The wax-bearing oil containing the said precipitate is again subjected to a high potential electric field between the central electrode 50 and the wall of the treater unit C, as in the first and second stages. Wax removed from the oil by deposition and settling is ejected from the system by means of pump 51. The high potential electric field between the wall of treater C and the central electrode is also supplied by means of a high voltage generator 25 through connecting conductor 26, switch 57 and lead-in insulating bushing 58. The electrical return circuit from the treater shell, as in treater units A and B, is completed through the ground and ground connection 30.

The oil from which wax has been removed in the first, second and third stages of treatment in treater units A, B and C, respectively, is withdrawn from treater unit C through line 65, valve 68 and lines 69 and 70 to the dewaxed oil storage tank 72.

In some cases the characteristics of the oil treated are such that in the latter stages of treatment the viscosity of the said oil becomes so great that continued treatment of the oil in additional stages is impossible without dilution. In this case a suitable diluent is supplied to any one of the stages of treatment from diluent storage tank 75 through suitable connections, such as shown in the drawing by line 76, valve 77 and

line 79. The diluent in line 79 joins and mixes with the wax-containing oil withdrawn from any one of the treater units, such as unit B, through line 45. The wax-bearing oil-diluent solution resulting from the mixture of the diluent from line 79 and the wax-bearing oil from line 45 proceeds through refrigerator 46 and valve 47 into the next stage of the treatment according to the process described hereinbefore. In some cases the characteristics of the wax-bearing oil undergoing treatment are such that dilution thereof is necessary in the initial treating stage in order to maintain sufficient fluidity and in this case the diluent from diluent storage tank 75 after flowing through line 76 and valve 80 is mixed with the wax-bearing oil in mixing valve 14. The solution of the diluent and wax-bearing oil resulting from said mixture in mixing valve 14 proceeds through line 15, refrigerator 16 and valve 17 into the initial stage of treatment in treater unit A, as described hereinbefore.

When diluents are employed in any of the stages of treatment, it is necessary to separate said diluents from the final dewaxed oil product and this is accomplished by means of distillation in a still 85. The dewaxed oil containing diluent in solution is withdrawn from the final treater C through line 65, valve 66 and introduced through line 67 into still 85. Heat is indirectly supplied to still 85 by means of heating coil 86. The bottoms from the still 85 comprising the dewaxed oil from which the diluent has been stripped is withdrawn through bottom outlet 87, valve 88, cooler 89 and run through line 70 to the dewaxed oil storage tank 72.

The diluent vapors removed from the dewaxed oil are withdrawn from still 85 through vapor line 90 and, where the diluent employed is normally liquid, the vapors are condensed in cooler 91 and returned by means of pump 92 through line 94 to the diluent storage tank 75. Where the diluent used is normally gaseous the vapors from the still are cooled in cooler 91, compressed in compressor 92, condensed in cooler 93 and the condensate returned through line 94 to the diluent storage tank 75.

When cooling or refrigeration of the wax-bearing oil in the treater unit A, B or C is accomplished directly, wholly or in part, by evaporation of a normally gaseous diluent the vapors are withdrawn from the tops of said treater units through vapor outlet connections 96, 97, 98 and pressure regulating valves 99, 100 and 101, respectively, and the said vapors compressed by means of compressor 102, cooled and condensed in cooler 93 and the condensate, as hereinbefore described, returned through line 94 to the diluent storage tank 75.

When it is advantageous to use electrolytes and/or finely divided solid materials in conjunction with the refrigeration and electrical treatment, according to the process of this invention, these materials may be mixed or dissolved in the diluent in storage tank 75 or in the wax-bearing oil in storage tank 10 prior to their introduction into the following treating stages.

Figure 1 of the drawing included herewith shows a three stage system of refrigeration and electrical treatment, but any other number of stages may be employed to obtain the desired pour point dewaxed oil product. The number of stages of refrigeration and electrical treatment required to obtain a dewaxed oil of the desired pour point when operating without dilution of the lubricating oil fraction or when operating with

a given degree of dilution of the said lubricating oil fraction is determined by means of a typical graph as shown in Figure 2. This graph comprises lines showing the cloud point and congealing point for a given wax-bearing lubricating oil fraction said lines being obtained by plotting wax percentage abscissa against oil solution temperature as ordinates, for the stated conditions. The cloud point line indicates the temperatures at which given concentrations of wax will start forming wax precipitates from solution. The solid line indicates the temperatures for given concentrations of wax at which the entire solution will solidify. The semi-plastic line between the cloud point line and the solid line indicates a region in which the mixture of oil and wax precipitate changes from a fluid to a semi-plastic state.

Multi-stage treatment must be confined to steps of refrigeration in which the temperature steps are such that the characteristics of the resulting mixture of wax-bearing oil and precipitate will lie chiefly in the region represented on the graph of Figure 2 between the cloud line and the semi-plastic line. The steps, or arrows, A, B, C, D, E, F, G, H and I show diagrammatically what may be expected and how many stages will be necessary for a multi-stage treatment of a given lubricating oil fraction. The horizontal portions of the said stepped line in the graph of Figure 2 represent the points during the stage and treatment of the lubricating oil fraction where the wax precipitate is electrically removed from the oil. The vertical portions of the said stepped line indicate the point in the multi-stage treatment where the temperature of the lubricating oil fraction is reduced following each of said points of removal of precipitated wax. Therefore, each pair of horizontal and vertical portions of the said stepped line represents the operations of one stage of treatment.

For example, starting with a 30% wax concentration in a solution of oil as represented in the graph of Figure 2, the first dewaxing stage would remove all dispersed solid wax precipitate particles at a temperature of 70° F. as indicated by the horizontal path A—B. The temperature of the fluid mass following this removal of wax would then be dropped to approximately 42° F. as indicated by the vertical path B—C, at which temperature, additional wax would be forced from solution into the solid phase and the mixture would again appear as a semi-fluid, semi-plastic mass. At this temperature the next dewaxing stage is carried out in which the additionally precipitated wax is removed as indicated by the horizontal path C—D. The process is continued in this manner through four stages, as represented in Figure 2, until a final temperature of approximately —25° F. is reached as a temperature at which the last separation of wax is conducted. Operation according to this graph accordingly produces an oil which has a pour point below —25° F. Obviously the pour point of the final product may be lowered or raised by employing more or fewer stages of such treatment.

Where the congealing or cloud point temperature of the waxy oil is normally above the atmospheric temperature, it will be necessary to apply heat to the mixture undergoing treatment in the initial step of the process with the subse-

quent steps of treatment carried on at successively lowered temperatures. When such heating of the oil prior to the initial stage of the electrical dewaxing process is necessary, such heat may be introduced by suitable heating means in the 5 wax-bearing oil storage tank '10.

The process and apparatus is not to be limited to the treatment of oils for the removal of wax but is applicable to the treatment of similar substances for the removal of asphalt, asphaltines, 10 petrolatum, sludges and other substances and impurities both solid and plastic.

The foregoing is merely illustrative of one apparatus and method and the invention is not limited thereby, but may include any method and 15 apparatus which accomplishes the same within the scope of the invention.

I claim:

1. A process for separating wax from wax-bearing oil comprising heating the wax-bearing 20 oil-wax mixture to a temperature at which it is a fluid containing wax precipitate, subjecting the thus heated mixture to an electric field and separating wax from the oil.

2. A process for separating wax from wax-bearing oil comprising heating the wax-bearing oil-wax mixture to a temperature at which it is a fluid containing wax precipitate, subjecting the thus heated mixture to an electric field and separating wax from the oil, cooling the said oil from 30 which wax has been removed to precipitate additional wax from solution, subjecting the oil containing the additionally precipitated wax to an electric field and separating additional wax from the oil. 35

3. In a process for separating wax from wax-bearing oil comprising cooling the wax-bearing oil to precipitate wax from solution, electrically depositing said wax precipitate on electrodes immersed in said wax-bearing oil, intermittently 40 reversing the polarity of said electrodes to dislodge deposited wax and allowing said dislodged wax to settle out of the oil.

4. A process for separating wax from wax-bearing oil which is congealed at ordinary temperatures comprising heating the wax-bearing oil to a temperature above its congealing point but below its cloud point, subjecting the thus heated mixture containing precipitated wax to an electric field and separating wax from the oil. 50

5. A process for separating wax from wax-bearing oil comprising heating the wax-bearing oil in the absence of a diluent, adjusting the temperature of the thus heated wax-bearing oil to a value at which it is a fluid containing wax precipitate, subjecting the thus treated mixture to an electric field and separating wax from the oil. 55

6. A process for separating wax from wax-bearing oil comprising heating the wax-bearing oil in the absence of a diluent to a temperature 60 above its pour point, subjecting the said oil to an electric field to separate a portion of the wax from the oil, adjusting the temperature of the said oil from which a portion of the wax has been thus removed to precipitate additional wax from 65 the oil, adding a diluent to the said oil from which a portion of the wax has been removed, subjecting the diluted partially dewaxed oil containing precipitated wax to an electric field and separating additional wax from the oil. 70
